Inventor
Auguste J. Lecoutre
By John L. Dickey
Attorney.

UNITED STATES PATENT OFFICE.

AUGUSTE J. LECOUTRE, OF WORCESTER, MASSACHUSETTS, ASSIGNOR TO ROYAL WORCESTER CORSET CO., OF WORCESTER, MASSACHUSETTS, A CORPORATION OF MASSACHUSETTS.

CORSET.

1,244,059.

Specification of Letters Patent. Patented Oct. 23, 1917.

Application filed April 13, 1916. Serial No. 90,865.

To all whom it may concern:

Be it known that I, AUGUSTE J. LECOUTRE, a citizen of the United States, residing at Worcester, in the county of Worcester and State of Massachusetts, have invented certain new and useful Improvements in Corsets, of which the following is a specification.

My invention relates to improvements in corsets, and particularly to that type of corsets, shown and described in U. S. Reissue Letters Patent No. 12,838.

The object of my invention is to improve upon the construction of the corset shown and described in said Letters Patent, and my invention consists in certain novel features of construction of my improvements.

In my improved construction of the corset referred to, the adjusting straps are under a section of the corset, at the front and side of the corset, and are substantially concealed. An elastic section is provided, as an additional reducer, which is at the lower part of the corset, at the front and side thereof, and back of the adjusting straps, all as will be hereinafter fully described.

Referring to the drawings:—

Figure 1 is a front, and partial side view of a corset, embodying my improvements.

Fig. 2 is a front or plan view of a detached section of the corset, shown at the left in Fig. 1.

Fig. 3 is a section, on line 3, 3, Fig. 2, looking in the direction of arrow a, same figure.

In the accompanying drawings, 1 is a front section of a corset, having the fastening clasps 1' thereon, 2 is the other front section of the corset, having the studs 2' thereon.

3 is a section having elastic webbing 3' therein. The section 3 extends from the lower edge of the corset nearly to the middle transverse line of the corset, and is preferably attached at its front edge to the inner edge of one of the steel sections of the corset, the section 1, as shown in Fig. 3, and at its rear edge to the side section 4, as shown in Fig. 3.

Extending on the outside of the webbing section 3, at the upper part thereof, are the two adjusting straps 5 and 6, shown by broken lines in Fig. 2. The strap 5 is attached in this instance to one of the steel sections, as shown in Fig. 3 to the section

1, and is provided with a metal loop 5' at its free end. The other strap 6 is attached in this instance to the edge of the side section 4 of the corset, as shown in Fig. 3, and has its free end 6', adapted to pass through the loop 5' on the strap 5, in the usual way.

On the outside of the adjusting straps 5, and 6, and extending over and substantially covering said straps, is a section 7 of the corset, which preferably extends from the upper edge of the corset to the lower edge, and is attached at its rear edge to a side section, as 4 in Fig. 3, and at its front edge to a front steel section, as 1 in Fig. 3. The section 7 has its lower edge, between the attached side edges, unattached and of curved shape, as shown at 7', and cut away so as not to extend over the main part of the elastic webbing section 3, as shown in Fig. 1.

The lower end of the section 7 has attached thereto one end of a looped hose supporter 8; the other end of said looped hose supporter 8 is attached to the lower end of the front section 1.

The section 7 extends over and substantially covers the two adjusting straps 5 and 6. The tongues 6' on the straps 6 extend out beyond the detached edge of the section 7 toward the rear of the corset, and are adapted to be taken hold of by the wearer of the corset, and drawn back toward the rear of the corset, to adjust the straps 5 and 6 and cause them to act as a reducer.

It will be understood that there is an elastic webbing section, two adjusting straps, and a strap-covering section, at each side or each half of the corset.

The adjusting straps on each side of the corset are substantially concealed by the covering section 7 and a tongue 6' on one of each pair of said straps extends on the outside of the corset and is thus in a position convenient to be taken hold of by the user in drawing up or tightening said straps. The elastic webbing sections extend beneath the adjusting straps and act as an additional reducer.

It will be understood that the details of construction of my improvements may be varied if desired.

Having thus described my invention, what I claim as new and desire to secure by Letters Patent is:—

1. In a corset, the combination with an elastic webbing section on each side of the

- 2
- corset at the front and lower part thereof, and a pair of adjusting straps on each side of the corset and outside of said webbing sections and having end portions extending 5 on the outside of the corset and thus conveniently accessible to the wearer for adjustment, of a section on each front outside of the corset extending over said adjusting straps and substantially covering the same.
- 10 2. In a corset, the combination with an elastic webbing section on each side, at the front and lower part thereof, of a pair of adjusting straps on each side of the corset and overlying said webbing sections, said 15 straps having end portions extending on the outside of the corset and thus conveniently accessible to the wearer for adjustment, a section on each front outside of the corset extending over said adjusting straps and
- substantially covering the same, and looped 20 hose supporters attached to said covering sections and to the front sections of the corset.
3. In a corset, the combination with a pair of adjusting straps on each side thereof, 25 said straps having end portions extending on the outside of the corset and thus conveniently accessible to the wearer for adjustment, of a section on each front outside of the corset, these outside sections being 30 independent of and extending over said adjusting straps and substantially covering the same.

AUG. J. LECOUTRE.
